UNITED STATES PATENT OFFICE.

OLEN A. COMP., OF BARBERTON, OHIO.

WATER-GLASS FRAME.

1,195,911.

Specification of Letters Patent. Patented Aug. 22, 1916.

Application filed February 11, 1916. Serial No. 77,760.

To all whom it may concern:

Be it known that I, OLEN A. COMP., a citizen of the United States, residing at Barberton, in the county of Summit and State of Ohio, have invented new and useful Improvements in Water-Glass Frames, of which the following is a specification.

The invention relates to a water glass frame, and more particularly to this type 10 of devices for use on locomotives, boilers, furnaces or the like.

The primary object of the invention is the provision of a water glass frame of this character wherein all danger is eliminated 15 of the frame or glass working loose with the resultant escape of water or steam.

Another object of the invention is the provision of a water glass frame wherein the glass is readily and easily removed and 20 is held in the frame without the use of bolts or screws and also eliminates the necessity of detaching the frame when the glass is to be removed therefrom.

A further object of the invention is the provision of a water glass frame wherein the same is rendered perfectly fluid-tight to 25 avoid leakage and also which permits the convenient removal of the glass or the insertion of packing, when the occasion requires, with despatch.

A still further object of the invention is the provision of a water glass frame of this character which is simple and practical in construction, thoroughly reliable and efficient in its purpose, strong, durable and inexpensive of manufacture.

With these and other objects in view, the invention consists in the features of construction and the combination and arrangement of parts hereinafter described, pointed out in the claims and illustrated in the drawings forming a part of this application.

In the accompanying drawings: Figure 1 is a front elevation of a water glass frame 45 constructed in accordance with the invention; Fig. 2 is a top plan view; Fig. 3 is a sectional view on the line 3—3 of Fig. 1; Fig. 4 is a fragmentary vertical longitudinal sectional view through the frame; Fig. 5 is 50 a vertical sectional view showing the body in elevation; Fig. 6 is a perspective view of the facing plate for the glass, looking toward the inner side thereof; and Fig. 7 is a fragmentary perspective view of the removable gasket.

Similar reference characters indicate cor-

responding parts throughout the several views of the drawings.

Referring to the drawings in detail, the water glass frame comprises a body 10 preferably of elongated rectangular shape, and is formed in its front face with a recess providing a seat 12 correspondingly shaped to and adapted to receive the water glass 13, while integrally formed with the said body 10, longitudinally of the same at its center, is a pipe-like water course 14, while the body at opposite sides of the pipe-like portion 14 is transversely beveled and longitudinally tapered to provide wedging and locking flanges 15 for the detachable engagement thereon upon the body of a slide housing 16, hereinafter fully described.

The slide housing 16 has formed in its front wall an elongated longitudinally disposed slot 17 forming a sight opening for the glass 13, which has disposed on opposite sides thereof the gaskets 18, the one at the front of the said glass being fitted within a facing frame 19 preferably made from metal 20 and having a slot 20 centrally therein, correspondingly shaped to and adapted to register with the slot 17 in the front of the housing so that the height of the water within the body 10 is clearly visible through 25 the glass on inspecting the gage.

The opposite side walls of the housing 16 are formed with locking flanges 21 beveled and tapered reversely to the flanges 15 and which coöperate with the said flanges 15 for 30 the wedging of the housing 16 upon the body 10 and also to prevent the lateral spreading of the sides of the said housing when the latter is mounted upon the body to fasten the glass 13 in the latter and also the gaskets 35 95 which prevent leakage and render the gage fluid-tight.

Upon one side of the body 10 are formed ratchet teeth 22, while mounted in a bearing 23 on one side wall of the housing 16 100 and working through and opening the slot 24 therein is a spring-held locking pawl or latch 25 which engages with the teeth 22 on the body 10 to lock the housing 16 thereon.

The housing 16, when removed from the body 10 of the water gage, is inserted upon the upper end of the said body and by a blow downwardly thereon the same will be forced into position for the wedging of the said housing on the body and thereby fastening the glass 13 and the gasket 18 to render the gage fluid-tight. It will be clearly

apparent that upon removal of the housing 16 from the body 10 the glass can be detached and also new gaskets replaced should occasion require.

6 From the foregoing description, taken in connection with the accompanying drawings, the construction and manner of operation of the device will be understood and, therefore, a more extended explanation has 10 been omitted.

Having thus described my invention, I claim:

13 1. A water glass gage comprising a body having a glass receiving seat therein and also provided with transversely beveled and longitudinally tapered locking flanges, a housing removably fitted upon the body and having reversely beveled and tapered locking flanges coöperative with the flanges on the 20 body for the wedging and locking of the housing thereon, and a glass arranged in the seat and held therein by the housing.

25 2. A water glass gage comprising a body having a glass receiving seat therein and also provided with transversely beveled and longitudinally tapered locking flanges, a housing removably fitted upon the body and having reversely beveled and tapered locking flanges coöperative with the flanges on the 30 body for the wedging and locking of the housing thereon, a glass arranged in the seat and held therein by the housing, and means disposed at opposite sides of the glass for preventing leakage through the seat 35 about the latter.

3. A water glass gage comprising a body having a glass receiving seat therein and also provided with transversely beveled and

longitudinally tapered locking flanges, a housing removably fitted upon the body and 40 having reversely beveled and tapered locking flanges coöperative with the flanges on the body for the wedging and locking of the housing therein, a glass arranged in the seat and held therein by the housing, means disposed at opposite sides of the glass for preventing leakage through the seat about the latter, ratchet teeth formed on the body, and a spring-held latch carried by the housing 45 and engageable with the teeth to lock the housing upon said body.

4. A water glass gage comprising a body having a glass receiving seat therein and also provided with transversely beveled and longitudinally tapered locking flanges, a 50 housing removably fitted upon the body and having reversely beveled and tapered locking flanges coöperative with the flanges on the body for the wedging and locking of the housing therein, a glass arranged in the 55 seat and held therein by the housing, means disposed at opposite sides of the glass for preventing leakage through the seat about the latter, ratchet teeth formed on the body, a spring-held latch carried by the housing 60 and engageable with the teeth to lock the housing upon said body, the said housing being formed with an elongated slot longitudinally thereof to make visible the glass in the seat.

In testimony whereof I affix my signature in presence of two witnesses.

OLEN A. COMP.
